His ATTORNEY

UNITED STATES PATENT OFFICE.

JOHN BOPP, OF BROOKLYN, NEW YORK.

MACHINE-PLANER HEAD.

SPECIFICATION forming part of Letters Patent No. 437,329, dated September 30, 1890.

Application filed April 28, 1890. Serial No. 349,779. (No model.)

To all whom it may concern:

Be it known that I, JOHN BOPP, a citizen of the United States, and a resident of Brooklyn, in the county of Kings and State of New York, have invented certain new and useful Improvements in Machine-Planer Heads, of which the following is a specification.

My invention relates to improvements in cutter-heads for machine-planers; and it is an improvement upon the invention patented to me as assignee of myself and John McCort by United States Letters Patent, dated February 4, 1890, and numbered 420,569.

In the drawings hereof the same reference letters indicate the same parts in all the figures.

Figure 1 illustrates an end view of the cutter-head, all but one corner thereof being broken away, and shows the method of attaching the cutter to the head and the peculiar construction of the head. Fig. 2 illustrates a side elevation of the parts shown in Fig. 1. Fig. 3 illustrates an end sectional view of an alternative construction of the cutter-head, the section being taken between two adjoining separate knives.

I refer to the said patent for a general description of the cutter-head, the arrangement of the parts, and the operation of the same, and shall confine the description and illustrations of this present application to those parts only which specifically relate to the present invention. In the said former patent the forward ends of the knives were confined by a shouldered bolt located beyond the edge of the head, which bolt was held to the head on a side at right angles to the side upon which the knife which it held rested. I have discovered that the knives can be supported as effectively for some purposes by throwing out brackets beyond the corners of the head, which shall not be broader than the width of the knives supported upon them, and thus there will be no part of the head proper which will come in contact with the lumber, and I do away with the external bolts and the labor of accurately fitting the shoulders on them relative to the height of the side of the head, as set forth in said former patent; and I have also discovered that if the metal of the head be cut away between the knives on a circle having a radius of sub-

stantially the distance between the axis of the head and the side thereof midway between two corners, then the result will be the same as when the brackets are used, and the size of the head as a whole may be reduced. I show both of these alternative forms in the drawings hereof.

Referring first to Figs. 1 and 2, A is the cutter-head. B are the brackets thrown out therefrom at its corners. They may be integral with the head or separate and fastened to it. C are the knives. D are the reinforce plates. They are not essential, but I prefer to use them. E are the rear bolts, which may be screwed into a straight hole tapped into the head, as shown in Fig. 3 at F, or they may have enlarged heads G, which work in a longitudinal undercut or dovetail groove H cut in the head, as in the other patent, and I are the bolts, which hold the front end of the knives. They may also have enlarged heads J, which fit and engage in a dovetail groove K cut longitudinally through the brackets, as shown in Figs. 1 and 2, or they may be screwed into threaded holes made in the brackets or their equivalent, as shown in Fig. 3. If the dovetail grooves are used, the knives may be more quickly and easily adjusted, and may also be shifted somewhat along the head.

In Fig. 3 I illustrate the alternative construction above referred to, in which the metal of the head is cut away between the knives on an arc L of a circle struck from the axis of the head, leaving only the parts M beneath the knives. It will be seen that this construction is in effect the same as the one first described, because the parts M are the same in operation and function as the brackets B, the only difference being that in one case the brackets are thrown out beyond the corners of the head, in which instance the radius of the circle free from contact with the lumber would be taken from the corner of the head, and in the other instance the circle will be defined by a radius from the axis to the middle of the side of the head between the corners, and in both cases the knives are supported upon brackets which project radially beyond the said circle.

I do not limit myself to the details of construction shown, since they may be somewhat

departed from and still the gist of my invention be employed.

I claim—

1. A cutter-head for planers, having bracket-like parts integral with the head, which are not wider than the knives and upon which the knives rest, the metal between the brackets being removed, substantially as set forth.
2. A cutter-head for planers, having bracket-like parts integral with the head, which are not wider than the knives and upon which

the knives rest, the metal between the brackets being removed, and a dovetailed groove running through the brackets, substantially as set forth.

Signed at Brooklyn, in the county of Kings and State of New York, this 26th day of April, A.D. 1890.

JOHN BOPP.
